UNITED STATES PATENT OFFICE

1,989,665

BURNER

Richard D. Cheesman, Hagerstown, Md., assignor
to Traylor Engineering and Manufacturing
Company, a corporation of Delaware

Application September 2, 1931, Serial No. 560,797

8 Claims. (Cl. 110—104)

This invention relates to burners.

An object of the invention is the provision of a burner using various types of fuel in connection with a source of air for producing flames of such types as will be required for a particular kind of work.

Another object of the invention is the provision of a self contained burner that will produce various forms and types of flames such as a long or short or an oxidizing or reducing flame.

A further object of the invention is the provision of a burner for producing various types of flames and with the burner being readily adjustable for producing such types of flames.

A still further object of the invention is the provision of a burner using either hot or cold air under pressure with the quantity of air and the degree of pressure aiding in controlling the type of flame produced.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

Figure 1 is a side view of a burner constructed in accordance with the principles of my invention and shown applied to a kiln for producing cement;

Figure 2 is a longitudinal and vertical section of the burner;

Figure 3 is a transverse vertical section, taken along the line 3—3 of Figure 2;

Figure 4 is a transverse vertical section, taken along the line 4—4 of Figure 2;

Figure 5 is a fragmentary horizontal section, taken along the line 5—5 of Figure 2; and

Figure 6 is a view in perspective of the gate valve for controlling the flow of air to one section of the burner.

Referring more particularly to the drawings, 10 designates a kiln, which may be employed for any suitable purpose such as the production of cement or the manufacture of lime. In place of the kiln, a metallurgical furnace may be substituted to be used in connection with the flame produced by my improved burner.

The arrangement in Figure 1 includes a burner unit 11, and a feeding hopper 12 having a reduced outlet passage 13 opening into the burner in a manner which will be presently described. The

hopper is supported by means of a framework, generally designated by the numeral 14, and this framework is supported from a platform 15.

Connected with the inlet end of the burner unit 11 is a pipe 20, which is in communication with a blower 21 of any approved construction. This fan or blower is driven in any approved manner by mechanism not shown.

An air pipe 22 connects the cyclone or air cleaner 23 with an air heater 24 which receives clinkers from an opening 25 in a platform 26 which supports a movable hood 26a adapted to embrace the outlet end of the burner unit 11 and the lower end of the kiln 10.

During the burning of the ingredients for the manufacture of cement in the rotary kiln 10 clinkers, as is well known, form, and these are discharged into the air heater 24 and discharged through a rotary cooler. This is more clearly shown in Fig. 1 in which a side portion of the air heater 24 is broken away to reveal the clinker material falling into a sloping trough leading into the elevated end of the inclined cooler. Air as indicated by the arrows in Fig. 1, is drawn through the pipe 22 over the heated clinkers through the heater 24, whence the blower 21 forces the heated air into the burner 11. By this construction the heat of the clinkers in the member 24 and in the rotary cooler 27 is partially transferred to the air while the clinkers are materially cooled.

The burner as shown in Figures 2 to 6, inclusive, includes an outer shell 30 and an inner tube or shell 31 which is co-axial with the outer tube 30, thereby providing an annular space 32 between the two shells for the passage of fuel and air. A valve 33 controlled by a shaft 34 is located near the inlet end of the tube or shell 31 so that by the regulation of this valve the amount of air entering the tube 31 will be regulated in accordance with the opening of the valve. Stops 35 secured to the inner walls of the tube 31 engage the valve and stop it in a normal vertical or closed position.

A semi-annular valve 40 closes the upper half of the annular passage 32 and is secured to a shaft 41 which is operated by a crank 42 for opening or closing the valve as may be desired. It will be noted that the central portion of the valve is cut away to provide an opening 43 to permit air to enter the inlet end of the tube 31 at all times regardless of the position of the valve 40. A valve 45 similar in construction to the valve 40, closes the lower half of the annular passage 32, and this valve is provided with an opening 46 which permits air at all times to enter the

inlet end of the tube 31. This valve is operated by a shaft 47 and crank 42 similar in construction to the shaft 41 and crank 42 of the valve 40. A plate 48 extends transversely of the tube 30 and between the bearings for the valve 40 and 45. It will be noted that the valve 45 engages an offset portion 49 at the inlet end of the tube 31.

The tube 31 is retained in its co-axial position within the tube 30 by means of bolts 50 threaded 10 into passages in the tube 30 and are locked in position by nuts 51. These bolts extend radially inwardly of the tube 30 and at approximately the same distance in order to obtain the desired co-axial relation of the tubes.

15 The discharge tube 13 for fuel extends downwardly through the tube 30 and terminates within the tube 31. The bottom of the discharge tube is closed, as shown at 55, and is inclined at an angle in order to direct the fuel through the opening 56 towards the outlet end of the tube 31.

20 The valve 57 is secured to a shaft 58 which is mounted in bearings within the tube 13 and is operated by a crank 59 shown in Figure 1. This valve closes a passage 60 in the discharge conduit 13 which registers with the upper portion of the 25 passage 32. When this valve is moved to the dotted line position, as shown at 57^a in Figure 2, it will open the passage 60 but close the lower end of the discharge conduit so that fuel will 30 enter the annular passage 32 instead of the inlet end of the tube 31.

25 The valve 33 is operated by a crank 49^a connected to the shaft 34. On the outlet end of the tube 31 is mounted a sliding sleeve 70 which is 35 provided with slots 71 adapted to receive pins 72 formed on the outer wall of the tube 31. This construction permits sliding of the sleeve 70 on the outlet end of the tube 31 by preventing rotation of said tube. Diametrically opposite links 40 73 are pivotally connected at 74 to the sleeve 70, and these links are pivotally connected at 75 with levers 76 which are rigidly secured to a shaft 77. This shaft is provided with a crank 78 located externally of the tube 30 so that the sleeve 70 45 may be reciprocated with facility.

The operation of my device is as follows:

50 Any type of fuel whether gaseous, liquid or solid may be employed, and supplied either from the hopper 12 or by means of additional equipment, depending upon the type of fuel employed. Whenever a solid fuel is employed, which is powdered before utilization, the tube 13 of the hopper 12 is preferable, since this powdered fuel may be fed from the hopper to the conduit 13 in any 55 preferred manner from the feeding box 12^a. A screw type of feed or any other type of feed suitable for the purpose may be used. If it be desired to employ the annular passage 32 for the fuel conduit, the valve 57 is moved to its dotted 60 line position 57^a in Figure 2, thereby preventing the passage of fuel to the conduit 31 which is supplied by air under pressure from the blower 21 and the quantity of air admitted to the tube 31 is controlled by the valve 33. A quantity of air 65 is admitted to the annular passage 32 by opening the valves 40 and 45 the proper degree in order to force the flame towards the outlet end of the tube 30. The quantity of air however which is admitted to the annular passage 32 depends upon 70 the type of flame desired. If a short flame is required for the purpose a greater quantity of air is admitted to the annular passage 32 while a long flame is produced by the introduction of a smaller quantity of air to the annular space 32. 75 The amount of air passing through the passage

32 may be so regulated to give complete combustion of the fuel at the burner or the outlet end of the tube 31. By introducing the fuel into the annular space 32 a reducing flame may be obtained. On the other hand, when the air in sufficient quantity is forced through the annular space 32 and the fuel is admitted to the tube 31, an oxidizing flame is produced. The ends of the tubes 30 and 31 coact in the sense that both contribute oxygen or fuel, or both, to maintain the 10 burner flame.

15 The length of the flame when the fuel is fed to the tube 31 is also controlled by the quantity of air admitted to the tube 31 with the fuel.

20 Reciprocation of the sleeve 70 during the burning of the mixtures tends to shorten or lengthen the flame, and the use of this sleeve depends upon the kind of work desired. If it be desired to extend the flame into the rotary kiln 10, in order to burn away the materials coating the inner 25 walls of the furnace, a long flame is necessary, and this is produced by introducing a smaller quantity of air with the fuel either in the tube 31 or the tube 30. By retracting the sleeve the flame will be proportionately shortened. 25

I claim:

1. A burner comprising an outer tube, an inner co-axial tube, the inner tube terminating short of the inlet end of the outer tube, means for supplying the air under pressure to the inlet end of the outer tube, the inner tube forming with the outer tube an annular space, a valve in the inner tube for controlling the flow of air to the inner tube, valves for controlling the flow of air through the annular space between the inner and outer tubes, common means for alternately supplying fuel to either the inner tube or to the annular space. 30

2. A burner comprising an outer tube, an inner co-axial tube, the inner tube terminating short of the inlet end of the outer tube, means for supplying air under pressure to the inlet end of the outer tube, the inner tube forming with the outer tube an annular space, a valve in the inner tube for controlling the flow of air to the inner tube, valves for controlling the flow of air through the annular space between the inner and outer tubes, a conduit connected with a source of fuel and extending through the outer tube and into open communication with the inner tube, the conduit having a passage opening into the annular space, a valve in the conduit adapted to close either the conduit to the inner tube or the passage to the annular space. 40

3. A burner comprising an outer tube, an inner co-axial tube, the inner tube terminating short of the inlet end of the outer tube, means for supplying air under pressure to the inlet end of the outer tube, the inner tube forming with the outer tube an annular space, a valve in the inner tube for controlling the flow of air to the inner tube, valves for controlling the flow of air through the annular space between the inner and outer tubes, means for supplying fuel to either the inner tube or to the annular space, means for alternately controlling the supply of fuel to either the inner tube or the annular space, the air valves adapted to be so regulated that a greater or less quantity of air may be supplied to the conduit which receives the fuel. 50

4. A burner comprising an outer tube, an inner co-axial tube, forming an annular space with the outer tube, means for supplying air under pressure to both tubes, a valve in the inner tube for controlling the flow of air to said tube, means 55

for supplying fuel to said tube between the valve and the outlet end of said tube, valves for controlling the supply of air to the space, the fuel supply means being in communication with the space, and means for controlling alternately the supply of fuel to either the space or the inner tube.

5. A multiple-tube burner comprising an innermost central tube and an outermost encircling tube in diametrically spaced relation with the central tube, said tubes having coacting outlet ends, means for supplying air under pressure to said tubes at points remote from said ends, a source of fuel supply, a conduit leading from the 10 source of fuel supply and communicating with the tubes intermediate the points of air supply and said ends, and control means operable for inversely varying the amount of fuel supplied to the respective tubes.
- 15 6. A multiple-tube burner comprising an innermost central tube and an outermost encircling tube in diametrically spaced relation with the central tube, said tubes having coacting outlet ends, means for supplying air under pressure to said tubes at points remote from said ends, a source of fuel supply, a conduit leading from the 20 source of fuel supply and communicating with the tubes intermediate the points of air supply and said ends, and a valve for closing communication 25 between the conduit and either one of the tubes while simultaneously closing communication between the conduit and the other tube, whereby the fuel delivered by the conduit may be discharged into either one of the tubes as desired 30 exclusively of the other tube.

7. A multiple-tube burner comprising an innermost central tube and an outermost encircling tube in diametrically spaced relation with the central tube, said tubes having coacting outlet ends, means for supplying air under pressure to said tubes at points remote from said ends, a source of fuel supply, a conduit leading from the source of fuel supply and communicating with the tubes intermediate the points of air supply and said ends, and a valve for alternately opening and closing communication between the conduit and tubes for dividing the fuel passing through the conduit and distributing it to the innermost and outermost tubes. 5

8. A multiple-tube burner comprising an innermost central tube and an outermost encircling tube in diametrically spaced relation with the central tube, said tubes having coacting outlet ends, means for supplying air under pressure to said tubes at points remote from said ends, a source of fuel supply, a conduit leading from the source of fuel supply and communicating with the tubes intermediate the points of air supply and said ends, and a valve for permitting communication between the conduit and either one of the tubes while simultaneously closing communication between the conduit and the other tube, whereby the fuel delivered by the conduit may be discharged into either one of the tubes as desired exclusively of the other tube. 15 20 25 30
